FIG. 1 is a front/top perspective view of a double-sided printed picture and frame in accordance with the present invention;

FIG. 2 is a front plan view thereof;

FIG. 3 is a right plan view thereof;

FIG. 4 is a rear plan view thereof;

FIG. 5 is a left plan view thereof;

FIG. 6 is a top plan view thereof; and,

FIG. 7 is a bottom plan view thereof.

Within FIGS. 1, 2 and 4, the broken lines represent exemplary printed images and text on the double-sided printed picture and frame and are not part of the claimed design. Additionally, the small rectangular features represent openings (i.e., perforations) in the double-sided printed picture and frame and are part of the claimed design.
